UNITED STATES PATENT OFFICE.

O. C. EVANS, OF NEW YORK, N. Y., ASSIGNOR TO HIMSELF AND L. D. TOWSLEY, OF SAME PLACE.

IMPROVEMENT IN FASTENINGS OF METALLIC BANDS FOR COTTON-BALES.

Specification forming part of Letters Patent No. 31,848, dated March 26, 1861.

To all whom it may concern:

Be it known that I, ORMROD C. EVANS, of the city and county of New York, and State of New York, have invented a new and improved mode of constructing hoop or band locks or fastenings which may be used in binding cotton-bales, hay, or straw, or casks and barrels, or other things wherein iron hoops or bands are used; and I do hereby declare the following is a full and exact description.

The nature of my invention consists in punching in and near each end of a short piece of hoop or band iron, or any other suitable material, a plain or corrugated slot of length and breadth sufficient to admit of passing through it such sized hoop or band iron as may be required; and also of raising out of the plate just behind each slot one or more angular tongues, of size and strength sufficient to admit of being bent back over the ends of the hoop or bands, and securely keep them in the position to produce the greatest impingement of the hoop or band upon the corners of the slots on both sides of the plate.

To enable others skilled in the art to make and use my invention, I proceed to describe its construction.

Figure 1 in the drawings is a face and edge view of the lock or fastening. Fig. 2 is a face and edge view of the lock with the ends of the hoop inserted.

In Fig. 1, letter A shows corrugated slots *s s* and tongues *t t t t*. Letter B shows tongues *t t* as raised out of the plate.

In Fig. 2, letter C shows a face view of the plate A, with the ends of the hoop or band *u u* secured therein. Letter D shows an edge view of the same.

What I claim, and desire to secure by Letters Patent of the United States, is—

The combination of the slots *s s* in the plate A with the angular tongues *t t t t*, more or less, as herein described, and for the purposes set forth.

ORMROD C. EVANS.
